COMBINED GAME CHIP HOLDER AND COASTER
TRAY OR THE LIKE

John W. Larrowe, 7609 Duchess Drive,
Whittier, Calif. 90606

Filed Dec. 8, 1969, Ser. No. 20,401

Term of patent 14 years

Int. Cl. D21—04

U.S. Cl. D34—13

Fig. 1.

Fig. 2.

Fig. 3.

FIG. 1 is a perspective view of a combined game chip holder and coaster tray or the like, showing my new design;

FIG. 2 is a rear elevational view thereof which is not shown in FIG. 1; and

FIG. 3 is an end elevational view of my design, the other end being the same.

I claim:

The ornamental design for a combined game chip holder and coaster tray or the like, as shown and described.
